UNITED STATES PATENT OFFICE.

WILLIAM HUNTER, OF GRINDSTONE CITY, MICHIGAN.

CAR-COUPING.

SPECIFICATION forming part of Letters Patent No. 292,820, dated February 5, 1884.

Application filed October 16, 1883. (No model.)

To all whom it may concern:

Be it known that I, WILLIAM HUNTER, a citizen of the United States, residing at Grindstone City, in the county of Huron and State of Michigan, have invented certain new and useful Improvements in Car-Couplers; and I do hereby declare that the following is a full, clear, and exact description of the invention, such as will enable others skilled in the art to 10 which it appertains to make and use the same.

In the accompanying drawings of my invention, Figure 1 is a general view. Fig. 2 is an end view. Fig. 3 is a sectional view.

15 A A' are the bunters, in each of which are pivoted freely the coupling-pins B B', by means of arms C C' passing through the sockets D D', and maintained therein. The weight of these pins will cause them to swing in an upright position unless pulled up by the short 20 levers E at side, to which chains will be connected, so as to be operated from the platform at end of car. The sockets D will be partially filled with a packing of rubber, F F', at each 25 side of projecting arms C C', so as to insure precision while allowing room for lateral pressure.

G G' are controlling-pins passing through farther ends of links, and easily removed. The action is as follows: The link H of the bunter A is passed into bunter A', and the link H' is received in opposite bunter, A, as the two are brought together. The pins B B' will then fall into place in the links, coupling the cars by both links, so that in the event of one of the links breaking or becoming detached the other one remains in position. 30

35 I claim as my invention—
A double-link car-coupler consisting of the combination of coupling-pins B B', arms C C', sockets D D', having elongated openings partially filled with rubber packing F F', short 40 levers E, controlling-pins G G', and double links H H', all arranged and operating substantially as shown and specified.

WILLIAM HUNTER.
